UNITED STATES PATENT OFFICE.

JOHN SCHWAB, OF WINNIPEG, MANITOBA, CANADA.

COMBINED HEATING SYSTEM FOR A PLURALITY OF BOILERS.

961,900.

Specification of Letters Patent. Patented June 21, 1910.

Application filed October 11, 1909. Serial No. 522,188.

To all whom it may concern:

Be it known that I, JOHN SCHWAB, of 5
Winnipeg, in the Province of Manitoba,
Canada, have invented certain new and use-
ful Improvements in Combined Heating
Systems for a Plurality of Boilers, of which
the following is a specification.

My invention relates to a combined heat-
ing system for a plurality of steam boiler
10 furnaces and the objects of my invention
are to provide means for economizing fuel
and obtaining all the heat units out of the
products of combustion of the fire in a fur-
nace.

15 It is well known that at present, a great
quantity of the heat units of combustion
pass up the chimney of a steam boiler fur-
nace, and it is proposed in the present case
to save these heat units by passing the prod-
20 ucts of combustion from the furnace of one
boiler through a second boiler, the said sec-
ond boiler having no fire in the furnace
thereof and being heated wholly by the
products of combustion from the furnace of
25 the first boiler.

In practicing the invention, a plurality
of steam boiler furnaces are suitably con-
nected together by conducting means in such
a manner that the products of combustion
30 from the fire in the furnace of one boiler
will pass through one or more additional
steam boiler furnaces. The steam boiler fur-
naces are preferably provided with the usual
smoke stacks and the conducting means hav-
35 ing controlling valves therein, so that each
steam boiler furnace may be used independ-
ently if desired.

40 The invention is more fully described
and set forth in the accompanying specifica-
tion and drawings.

In the drawings: Figure 1 is a horizontal
section through a pair of steam boiler fur-
naces having my invention combined there-
with, the section being taken on the line
45 2—2, Fig. 3. Fig. 2 is a vertical section
on the line 3—3, Fig. 1, looking in the direc-
tion indicated by the arrow. Fig. 3 is a sec-
tion on the line 4—4, Fig. 1. Fig. 4 is a sec-
tion on the line 5—5, Fig. 1.

50 It is evident that any number of steam
boiler furnaces may be combined according
to the present invention, and by way of

illustration, I have shown the combination
of two furnaces only.

Referring to the embodiment illustrated 55
in Figs. 1 to 4, A and B represent two steam
boiler furnaces of any usual or well known
construction, and which in the embodiment
illustrated are placed side by side, the front
of one furnace being adjacent to the end of 60
the next one. The furnaces A and B are
each provided with the usual grate bars
C C', and smoke outlet pipes D and E, the
said outlet pipes for the purposes of the
present invention being provided with suit- 65
able controlling valves 10 and 11 of any
well known construction. The boilers c and
d are of the usual construction.

In accordance with the present invention,
the rear of the furnace A communicates with 70
a conduit F which leads to the front end of
the furnace B, opening above the grate bars.
In order that the products of combustion
shall pass through this conduit instead of
going through the flues of the boiler c, it is 75
necessary to provide baffling means, and
the form I have illustrated comprises a slid-
able plate 12 adapted in innermost position
to cut off communication between the fur-
nace A and the boiler c, the said plate being 80
removable in order to permit the steam
boiler furnace to be used in the ordinary
way.

In order to permit the steam boiler fur-
naces to be used in the ordinary way, it is 85
necessary, in addition, to provide means for
closing the conduit F. The means I have
illustrated for this comprise a sliding plate
13 extending through the masonry and
adapted in innermost position to close the 90
conduit F.

The top of the front of the boiler d is also
placed in communication with the rear of
the top of the boiler c by means of a suitable
95 conduit G.

When the steam boiler furnaces are to be
heated by a single fire, the plate 12 is moved
to innermost position and the plate 13 is
withdrawn and a fire is lighted in the fur-
nace A. The products of combustion travel 100
over the baffle wall of the first furnace,
passing beneath the boiler c and imparting
part of their heat to the same. They then
pass through the conduit F into the front

end of the furnace B and then pass over the bridge wall of the furnace B, to the rear end, then through the flues of the boiler d back to the forward end then they pass 5 through the conduit G into the rear end of the boiler c. They then pass through the flues of the boiler c and out through the smoke pipe E, the valve in which has been opened, the valve in the smoke pipe D of the 10 steam boiler furnace B being closed.

It will be seen that the distribution of heat effected by this system is very uniform, because the first boiler is in contact with the products of combustion at first, when they 15 are highly heated, for a short time. The second boiler is then in contact with them for a longer time, and finally the first boiler is in contact with them for a short time again, thereby equalizing the distribution 20 of heat.

When it is desired to use the steam boiler furnaces independently, the plate 13 is moved to innermost position, and the plate 12 is withdrawn, and the valves in both 25 smoke pipes opened. It is not necessary to close the conduit G because the ordinary draft through the smoke pipe will prevent any flow through this conduit.

As many changes could be made in the 30 above construction, and many apparently widely different embodiments of my invention within the scope of the claims could be made without departing from the spirit or scope thereof, it is intended that all matter 35 contained in the accompanying specification and drawings shall be interpreted as illustrative and not in a limiting sense.

It is to be understood that the type of 40 steam boiler furnace shown is only illustrative and the invention may with facility be adapted to any type of boiler, whether bricked in or asbestos covered, stationary or marine, etc.

What I claim as my invention is:

45 1. The combination with two steam boiler furnaces disposed adjacent to each other and provided with boilers, of conducting means connecting the rear end of one furnace in one steam boiler furnace with the front end 50 of the furnace of the second steam boiler furnace and conducting means connecting the front end of the second boiler in the steam boiler furnace with the rear end of the boiler in the first steam boiler furnace and 55 means preventing the products of combustion in the furnace of the first steam boiler furnace from passing from the furnace of the same into the flues of its own boiler, whereby the products of combustion will be forced to pass from the front to rear of the 60 first furnace, then from front to rear of the second furnace and then successively through the flues of the boilers.

2. The combination with two steam boiler furnaces disposed adjacent to each other and 65 provided with boilers and having the head of one furnace adjacent to the rear end of the other furnace, of conducting means connecting the rear end of one furnace with the front end of the second furnace, conducting 70 means connecting the front end of the second boiler with the rear end of the first boiler, and means preventing the products of combustion in the first furnace from passing into the flues of the first boiler, whereby the 75 products of combustion will be forced to pass first, beneath the first boiler to the rear end of the same, then pass from the front to the rear of the second boiler, then through the flues of the second boiler and then 80 through the flues of the first boiler.

3. The combination with two steam boiler furnaces disposed adjacent to each other and provided with boilers, of conducting means connecting the rear end of one furnace with 85 the front end of the second furnace, conducting means connecting the front end of the second boiler with the rear end of the first boiler, baffling means for preventing the products of combustion in the first furnace 90 from passing into the flues of the first boiler, whereby the products of combustion will be forced to first pass beneath the first boiler to the rear end of the same, then pass from the front to the rear of the second boiler, then 95 through the flues of the second boiler and then through the flues of the first boiler, and means for withdrawing the baffling plates and closing the conducting means to enable the steam boiler furnaces to be used independently. 100

4. The combination with a pair of steam boiler furnaces boilers therein each having suitable flues therein, of means for conducting products of combustion passing beneath 105 the first boiler to beneath the second boiler, then through the flues of the second boiler and thence through the flues of the first boiler, the second steam boiler furnace adapted to have no fire therein. 110

5. The combination with a pair of steam boiler furnaces placed side by side and provided with boilers, of means preventing the products of combustion in the first furnace from passing into the flues of the first boiler, 115 conducting means conducting said products of combustion to beneath the second boiler and conducting means permitting the passage of the products of combustion from the second boiler to the flues of the first boiler 120 after they have passed through the second boiler, the said second steam boiler furnace adapted to have no separate fire therein. 125

6. The combination with a plurality of steam boiler furnaces boilers therein having 125 separated flues, of means for conducting the

products of combustion of a single fire beneath all the boilers and then successively through the flues of the boilers.

7. The combination with a plurality of 5 steam boiler furnaces each having separate water heating means, the furnaces of the boilers all adapted to be idle, except one, of means for conducting the products of combustion of the active furnace through the 10 entire lengths of the idle furnace or furnaces

and then successively through the water heating means of all the steam boiler furnaces.

In witness whereof I have hereunto set my hand in the presence of two witnesses.

JOHN SCHWAB.
